UNITED STATES PATENT OFFICE.

EDWARD T. POLLARD, OF RICHMOND, VIRGINIA, AND FRANK J. LUDINGTON, OF WATERBURY, CONNECTICUT.

CORKSCREW.

SPECIFICATION forming part of Letters Patent No. 406,304, dated July 2, 1889.

Application filed December 14, 1888. Serial No. 293,583. (No model.)

To all whom it may concern:

Be it known that we, EDWARD T. POLLARD, of Richmond, county of Henrico, State of Virginia, and FRANK J. LUDINGTON, of Waterbury, in the county of New Haven and State of Connecticut, have invented a new Improvement in Corkscrews; and we do hereby declare the following, when taken in connection with accompanying drawings and the letters of reference marked thereon, to be a full, clear, and exact description of the same, and which said drawings constitute part of this specification, and represent, in—

Figure 1, a front view of the device with the screw in the down position; Fig. 2, a side view of the same, looking from the left of Fig. 1; Fig. 3, a top view; Fig. 4, a vertical central section showing side view of the mandrel; Fig. 5, a vertical section through the barrel, the mandrel removed, showing the shoe; Fig. 6, a transverse section through the barrel, showing top view of the shoe; Fig. 7, a side view of the mandrel, looking from the left of Fig. 4; Fig. 8, a modification in the means for 25 rotating the mandrel.

This invention relates to an improvement in that class of corkscrews which are designed to be secured to some stationary point and so that much greater power may be applied than 30 can be done in the usual hand-corkscrews, the object of the invention being to produce both the entering and withdrawing movement of the corkscrew without changing the direction of the operating-lever; and it consists in the 35 construction as hereinafter described, and more particularly recited in the claims.

A represents a tubular barrel or cylinder, in which the mandrel of the screw is arranged. This barrel is provided with a suitable bracket 40 B, by which it may be secured in a fixed position in the usual manner for this class of corkscrews. The lower end of the barrel A is made flaring, also as in the usual construction, to receive the neck of the bottle and 45 support it against the draft of the screw.

C is the mandrel, the external diameter of which corresponds to the interior of the barrel A, and the mandrel at its lower end is provided with a screw D, as in the usual construction. The mandrel in its lower portion

is screw-threaded; but the screw is cut double-acting—that is, both right and left hand—as seen in Fig. 4, the threads being alike in both directions and so that the grooves between the ribs cross each other, as shown. A rotative movement is imparted to the mandrel through a bevel-pinion E, supported on a bearing F on the upper end of the barrel, the said pinion being held against movement in an axial direction, but yet free to revolve. It 55 is here represented as so held by constructing the hub of the pinion with an annular groove G and a hook H, secured to the side of the barrel, the nose I of which rests in the groove of the hub. Several of these hooks may be applied, 60 if desired. The means for holding the pinion against movement in an axial direction, but leave it free to revolve, is immaterial, it only being essential that it shall be so held. The mandrel works through the pinion. The 65 one is provided with a spline J, and the other with a corresponding groove K, as seen in Fig. 3, so that the mandrel is free to move in an axial direction through the pinion, but yet the one must partake of the rotation of 70 the other. Into this pinion a corresponding gear L is arranged to work, this gear, as here represented, being supported upon an axle M, stationary on the barrel, and so that the gear L may revolve freely thereon, and the 75 gear is provided with a suitable lever or crank N, by which rotative movement may be imparted to the gear L, the gear L and pinion E being correspondingly toothed, and so that the rotation of the gear L will impart corresponding rotation to the pinion E, and this rotation will be communicated to the mandrel C.

Within the barrel a shifting-shoe P is hung upon a pivot, as seen in Figs. 5 and 6, the axis 80 of the pivot being at right angles to the axis of the mandrel. This shoe in thickness corresponds substantially to the depth of the spiral groove in the mandrel, and at its widest portion corresponds to the width of the groove, that 85 widest portion being in the central line of the pivot, and from that central line the shoe diminishes in width toward its end, terminating in substantially sharp edges. This shoe is adapted to rock on its pivot, as indicated 90

in broken lines, Fig. 5, and as it corresponds to the spiral groove of the mandrel it follows that as the mandrel is rotated its spiral groove will work over that shoe, and the shoe being 5 stationary, the mandrel will receive a vertical movement under such rotation corresponding to its spiral groove. The mandrel being at its highest position, as represented in broken lines, Fig. 4, the lowest portion of the rib or 10 screw-thread rests upon the shoe P. Now, if the mandrel be rotated to the right, the shoe P will turn corresponding to the right-hand spiral groove of the mandrel, and so that that right-hand spiral groove will work over the 15 shoe and correspondingly draw the mandrel downward until the extreme down position of the mandrel is reached, as represented in Fig. 4. There the right-hand spiral groove runs into the left-hand groove, as seen in Fig. 20 7, and the rotation of the mandrel continued. That left-hand groove now engages the shoe, turning it to an inclination corresponding thereto, the result of which is that the continued rotation of the mandrel will now, 25 through the left-hand groove, cause the mandrel to rise until the extreme up position is attained, where again the left-hand groove at the lower end will run into the right-hand, as seen in Fig. 7, and so that the shoe will be 30 again turned, as indicated in broken lines, Fig. 7, and the continued rotation of the mandrel still in the same direction will cause the descent of the mandrel as before. This double 35 right and left hand thread, with the rocking shoe, is a well-known mechanical movement for imparting reciprocating movement.

The pitch of the right and left screw-thread of the mandrel corresponds to the pitch of the thread of the corkscrew, so that if when 40 the mandrel is in its up position a bottle be introduced to the mouth of the barrel below and there held the rotation of the mandrel will first cause the corkscrew to enter the cork until the mandrel reaches its down position. Then the continued rotation of the mandrel will cause the mandrel to rise, and with it the corkscrew and the cork into which it has entered, and thus the cork will be drawn from the bottle. Then, as the best manner 45 50 for removing the cork from the corkscrew, the mandrel is rotated in the opposite direction, which will cause it to descend, the same as if rotated in the right-hand direction, and until it reaches its down position; there the cork being grasped by one hand, while the other continues the left-hand rotation of the mandrel, the screw will be withdrawn from the cork.

The proportions of the gears through which 60 the mandrel is rotated are best made with reference to the number of rotations required for the mandrel—that is to say, if, as here represented, six full revolutions of the mandrel be required for the descent and ascent 65 of the mandrel, the pinion E is made one-third the diameter of the gear L, so that two

full revolutions of the gear L will impart the said six full revolutions to the mandrel and give its descent and ascent, leaving the mandrel at its up position ready for the next 70 operation. The position of the handle being up will indicate that the mandrel is in the proper position for operation. It will be evident that the arrangement of the gears may be varied to suit circumstances. 75

In some cases the gears may be omitted entirely and a lever or crank applied directly to the mandrel, as seen in Fig. 8. While, therefore, preferring the gear-connection, as we have described, we do not wish to be understood as limiting the invention to the employment of the gears. 80

We claim—

1. In a corkscrew, the combination of a tubular barrel constructed at its lower end to 85 form a seat for the neck of a bottle, a mandrel arranged to work vertically in said barrel and provided at its lower end with a corkscrew, the said mandrel constructed with a right and left hand screw-thread, the said 90 threads corresponding substantially to the screw-thread of the corkscrew, and the said spiral grooves of the threads on the mandrel crossing each other, a rocking shoe arranged upon a pivot within the barrel and adapted 95 to engage either the said right or left hand thread on the mandrel, and means, substantially such as described, to impart rotation to said mandrel, and whereby under such rotation of the mandrel it will be caused to descend and then ascend without change in the direction of rotation. 100

2. The combination of the tubular barrel A, the mandrel C, arranged therein, said mandrel provided with a corkscrew at its 105 lower end and constructed with a right and left hand screw-thread upon its surface, the spiral grooves of the said threads crossing each other, a rocking shoe P, supported upon a pivot upon the inside of the barrel, the said 110 shoe corresponding to the said grooves on the mandrel and adapted to engage either as they are presented, a pinion E, arranged upon said barrel concentric with said mandrel, and through which the said mandrel works, the 115 said pinion free for rotation, but held against movement in an axial direction, said pinion and mandrel, the one constructed with a spline and the other with a corresponding groove, and a gear, as L, arranged to work 120 into said pinion and provided with a suitable lever, whereby rotative movement may be imparted to said gear, substantially as described. 125
